ORNAMENTAL CONSTRUCTION

Howard F. Reichenbach, Waterbury, Conn., assignor to The Chase Companies, Incorporated, Waterbury, Conn., a corporation of Connecticut

Application October 16, 1935, Serial No. 45,265

2 Claims. (Cl. 131—51)

This invention relates to ornamental constructions, and particularly to ornamental constructions having one or more molded-composition pieces mounted on a metal body-member.

5 One object of this invention is to provide an improved ornamental construction having molded composition pieces mounted on a metal body-member by means of concealed attaching-means, in such manner as to give the maximum attractive appearance to the finished article.

10 With the above and other objects in view, this invention includes all improvements over the prior art which are disclosed in this application.

15 In the accompanying drawing, in which one way of carrying out the invention is shown for illustrative purposes:

Fig. 1 is a perspective view illustrating one embodiment of the invention and having molded-composition pieces mounted on a metal body-member;

20 Fig. 2 is a fragmental perspective view of a portion of Fig. 1, with one of the molded-composition pieces removed;

Fig. 3 is a fragmental sectional view on line

25 3—3 of Fig. 1;

Fig. 4 is a rear perspective view of one of the molded-composition pieces;

Fig. 5 is a front perspective view of one of the molded-composition pieces; and

30 Fig. 6 is a bottom plan view of one of the molded-composition pieces.

In the description and claims, the various parts are identified by specific names for convenience, but they are intended to be as generic in their 35 application as the prior art will permit.

Referring to the drawing, an ash tray 10 is formed of sheet-metal and has a plurality of pieces of molded-composition, such, for example, as bakelite, in the form of cigar or cigarette rests 40 11 secured to the body-member 10. Each cigar rest 11 has an attaching-member 12 embedded therein when the molded-composition piece is manufactured.

The attaching-member 12, in the form shown 45 in the drawing, consists of a threaded bolt, pref-

erably having a head 13 which may, if desired, be in the form of a hexagon, or in any other desired form, preferably non-circular, in order to prevent rotation of the bolt 12.

The pieces 11 are secured in position by passing the bolts 12 through holes 14 in the rim 15 of the metal body-member 10 and securing nuts 16 on the ends of the bolts 12.

In order that the molded-composition pieces 11 may not project out unduly far beyond the rim 15, depressed areas 17 are formed in the rim 15 with edge-boundaries 18 and 19 a sufficient distance apart to receive therebetween the opposite side-edges 20 and 21 of a molded-composition piece.

The invention may be carried out in other 15 specific ways than that herein set forth without departing from the spirit and essential characteristics of the invention, and the present embodiment is, therefore, to be considered in all respects as illustrative and not restrictive, and all 20 changes coming within the meaning and equivalency range of the appended claims are intended to be embraced therein.

I claim:

1. An ornamental construction comprising: a 25 metal body member; and one or more ornamental molded-composition pieces mounted on said body member and each having two legs and being of L-shape cross-section with one leg shaped to conform substantially to the side surface of the body 30 member and the other leg conforming to the top surface of the body member, each of said pieces being mounted by concealed threaded attaching means having part thereof molded in the piece.

2. An ash tray comprising: a metal body member including a rim; and one or more molded-composition cigar-rest pieces mounted on said rim and each having two legs and being of L-shape cross-section with one leg shaped to conform substantially to the side surface of the body 40 member and the other leg conforming to the top surface of the body member, each of said pieces being mounted by concealed attaching means having part thereof molded in the piece.

HOWARD F. REICHENBACH.
